Attorney

UNITED STATES PATENT OFFICE.

WILLIAM SCHREIBER, OF SYRACUSE, NEW YORK.

GARMENT-SUPPORTER.

1,230,800.

Specification of Letters Patent. Patented June 19, 1917.

Application filed June 28, 1916. Serial No. 106,472.

To all whom it may concern:

Be it known that I, WILLIAM SCHREIBER, a citizen of the United States, residing at Syracuse, in the county of Onondaga and State of New York, have invented certain new and useful Improvements in Garment-Supporters, of which the following is a specification, reference being had to the accompanying drawings.

10 This invention relates to an improved garment supporter and has for its primary object to provide a simple, effective and durable device for supporting men's and boys' undergarments.

15 It is another and more particular object of the invention to provide a supporter for the undergarment which may be easily and quickly attached or removed and can be employed either when a belt or suspenders 20 are worn.

It is one of the more specific objects of the invention to provide a device for the purpose above stated, consisting of a body plate having a headed stud thereon, a resilient 25 clamp or fastener loosely connected at one of its ends to the body plate having opposed portions adapted to clamp the material of the garment against opposite sides of the stud shank, and means for detachably 30 holding the other end of the fastener in connection with said plate.

With the above and other objects in view, my invention consists in the novel features 35 of construction, combination and arrangement of parts to be hereinafter more fully described, claimed and illustrated in the accompanying drawing, in which,

Figure 1 is a perspective view showing the device applied to the waist band of the 40 trousers;

Fig. 2 is a vertical sectional view thereof; and

Fig. 3 is an elevation showing one end of the resilient fastener or clamp detached 45 from the body plate.

Referring in detail to the drawings, 5 designates the body plate of my improved supporter which is preferably constructed of aluminum and of elongated form. This 50 plate is bent upon itself in spaced relation to one of its ends, as shown at 6, to provide the clamping tongue 7 extending in approximately parallel relation to the body of the plate. Adjacent to the bend 6 of the 55 plate, laterally projecting ears 8 are formed

upon the opposite longitudinal edges thereof, said ears being apertured, as at 9.

Adjacent to the other end of the plate 5, a stud or shank 10 is securely fixed thereto and projects from one face of the plate. 60 The end of this stud is formed with a circular head 11.

The clamp or fastener is formed from a single length of resilient wire which is bent intermediate of its ends to provide a spring 65 coil 12 therein and arms 13 normally extending in divergent relation from said coil. The terminal of one of the arms 12 has an eye 14 formed therein which is engaged through the aperture 9 in one of the ears 70 8. The other of said arms has its terminal angularly bent as at 15, for detachable engagement through the aperture 9 in the other ear 8.

In the use of my improved supporter, the 75 clamping hook 8 on the end of the plate 5 is engaged over the upper edge of the waist band of the trousers, as clearly seen in Fig. 1, the body portion of said plate extending downwardly upon the inner side of the 80 trousers and between the same and the waist band of the undergarment. The fastener being disconnected from one of the ears 8 as shown in Fig. 3 of the drawing, said fastener is engaged over the inner side of the 85 upper edge of the undergarment and one of the arms 13 is disposed upon one side of the stud 10. The other arm 13 is then forced inwardly against the opposite side of the stud over which the material of the undergarment is engaged, and the angularly extending terminal 15 of said arm forced 90 inwardly of the ear 8 on the body plate so that when pressure on the arm is released, the angular end thereof will be projected 95 outwardly over the aperture in said ear, as will be readily understood. Thus, the undergarment will be securely clamped or fastened to the body plate 5 and properly supported with respect to the trousers. Any 100

desired number of these garment supports may be used, but preferably two are employed in front and two at the back. The use of my improved fastener in no wise interferes with the use of the usual trousers 105 supporting belt or suspenders, as may be preferred by the wearer.

From the foregoing description, taken in connection with the accompanying drawing, the construction, manner of use and several 110

advantages of my invention will be clearly and fully understood. The device, while exceedingly simple, is very effective and reliable in practical use and highly serviceable 5 and convenient. I have herein referred to the invention as particularly designed for supporting men's undergarments, though it will be manifest that the supporter may be subsequently employed for various other 10 analogous purposes.

While I have shown and described the preferred form and construction of the several features of the device, it is to be understood that the invention is susceptible of 15 considerable modification therein and I, therefore, reserve the privilege of adopting all such legitimate changes as may be fairly embodied within the spirit and scope of the invention as claimed.

20 Having thus fully described my invention, what I desire to claim and secure by Letters Patent is:—

1. A garment supporter including a sheet metal body plate having an attaching hook 25 formed on one end and ears angularly projecting from the longitudinal edges of the plate adjacent to said hook, a headed stud fixed in the plate adjacent its other end, and a clamping member formed from a length 30 of resilient wire centrally bent to provide normally diverging arms, one of said arms having terminal means loosely and pivotally connected to one of the ears on the body

plate, said arms being adapted to clamp a garment against opposite sides of the headed 35 stud and the other arm having terminal means for detachable engagement with the other of said ears when the arm is forced toward the first named arm, whereby the arms are held in clamping engagement with 40 the garment.

2. A garment supporter including a body plate having an attaching hook formed on one end, a headed stud projecting from one 45 face of the plate adjacent to its other end, said plate being provided upon its longitudinal edges with opposed apertured ears, and a clamping member formed from a single length of resilient wire having a spring coil 50 therein intermediate of its ends and clamping arms normally extending in divergent relation to each other from said coil, one of 55 said clamping arms being permanently and pivotally connected to one of the ears, said arms being adapted to clamp the garment against the opposite sides of said stud and the other clamping arm having its terminal angularly disposed for detachable engagement through the other of the apertured ears.

60 In testimony whereof I hereunto affix my signature in the presence of two witnesses.

WILLIAM SCHREIBER.
